STORAGE TANK

Alexander F. Fino and Fred L. Plummer, Warren,
Pa., assignors to Hammond Iron Works, Warren,
Pa., a corporation of Pennsylvania

Application June 13, 1951, Serial No. 231,408

12 Claims. (Cl. 220—85)

1 This invention relates to steel storage tanks for vaporizable liquids such as gasoline, in which the contents of the tank, for example high octane gasoline and any of its valuable vapor volume above the liquid are to be sealed against the atmosphere by means of a diaphragm of gas-impermeable flexible material peripherally fastened to the inner face of the tank along a horizontal line intermediate the top and bottom of the tank.

Such a diaphragm may be generally bucket-shaped and capable of bulging downwardly or upwardly from the line of fastening so as to adjust itself automatically to variations in the volume of the gasoline or of the vapor or of both in the tank, while the weight of the diaphragm exercises a substantially fixed although light counter pressure upon the fluids or vapor in the tank.

Such a diaphragm is fastened to the tank wall by means of a flange connected gas-impermeably with the tank as well as with the peripheral edge portion of the diaphragm, which flange is normally of minimum width to minimize the extent of its projection into the tank, in order that any hindrance by the fastening means or interference between the diaphragm and the fastening means be avoided, and that optimum smoothness in the operation of the diaphragm might be attained.

In accordance with such volumetric variations of the contents the bottom portion of such a bucket-shaped diaphragm will move upwardly or downwardly between extreme upright and inverted position of the bucket shape, with the bottom portion moving upwardly or downwardly past the peripheral diaphragm securing line and through the effective opening of the flange. Indeed, in one embodiment of such a diaphragm the construction thereof is such that when the bottom portion moves upwardly or downwardly it forms in its intermediate stages an annular depending fold concentric with the periphery, the diameter of which fold decreases as the bottom portion moves either downwardly or upwardly towards the line of fastening. In this way the bottom portion may in effect shrink to a minimum as the bottom portion moves through the flange opening and again expand as it moves away from the flange until it reaches either its lower end position in the fully developed upright bucket shape or its upper end position in the fully developed although inverted bucket shape of the diaphragm. Other embodiments are possible that offer a solution to this problem, so this one should be taken as illustrative.

This effective shrinking and expanding of the

2 diaphragm in the operation of some type of diameter-reducing folding keeps the diaphragm out of frictional sliding contact with the tank walls and thus avoids harmful abrasive action between the wall and the diaphragm material. Instead, when adjusting itself volumetrically to the varying contents of the tank the diaphragm will roll itself onto or unpeel itself from the tank wall non-frictionally.

Such a diaphragm may be disposed to operate at least in partial contact with or resting upon the liquid with the annular fold depending into the liquid, or it may be arranged to operate so that it normally is in contact only with the vapor above the liquid. In each instance of arrangement or operation a problem arises if and when it is desired to provide inside the tank suitable structure jutting from the wall from which an operator could inspect and survey the diaphragm or from which its operation could be observed, since, on the face of it, such structure would be expected to interfere with or obstruct the operation of the diaphragm.

Another problem in a diaphragm-equipped tank lies in how to provide automatic vent means for equalizing excessive pressure as well as vacuum, or a sample-pipe, or both extending through the top of the tank and into the body of liquid with the diaphragm interposed as a septum or obstacle. Indeed, a baffling problem lies in how to provide straight vertical vent and sample pipes within the tank without penetration of the diaphragm.

Therefore, it is one object of this invention to provide internal platform structure which is non-interfering with respect to the operation of the diaphragm.

Another object is to provide a simple and inexpensive arrangement of vent and sample pipes extending within the tank and reaching from above the top to a point below the diaphragm, whereby the diaphragm is nevertheless bypassed even though the pipes are straight and vertical.

Whereas one or more manholes may be provided in the tank walls, and whereas such manholes require maintenance, a particular problem lies in providing simple and direct passage means between the tank space below the diaphragm and the tank space above the diaphragm, so that fresh air may be forced sequentially and effectively through the lower tank space and the upper tank space for the purpose of scavenging the entire interior of the tank for rendering it gas free. Another purpose of such passage means according to this invention is that of enabling workmen

to enter the lower tank space from above or to enter the upper tank space from below the diaphragm expeditiously, or to enable a crew below to communicate with a crew above the diaphragm as directly as possible. Hence, it is an object to provide simple and direct access to the interior of the tank below the diaphragm namely without penetration of the tank wall, as well as without penetration of the diaphragm.

All three objects are attainable at once according to this invention by having the internal flange include and formed with or embodying in it a horizontally inwardly protruding platform whereby the flange opening in plan view presents a deviation from the circular outline of the tank, and having the edge portion of the diaphragm fastened to the flange along the deviated outline thereof. Indeed these objects are thus attainable because of the discovery that such deviation if suitably formed and proportioned is non-interfering and non-obstructive with respect to the operation of the diaphragm such as above outlined. According to this invention, the vent and sample pipes are disposed to extend through and be sealed in the platform itself, thus enabling them to extend fixedly straight from outside the top to a point below the platform, thus bypassing the diaphragm as well as the tank wall and leaving the diaphragm to operate properly and unaffected. Furthermore, in order to afford access to the tank interior below the diaphragm, a manhole with detachable cover may be provided in the platform. In this way access is obtainable while bypassing the diaphragm as well as the tank wall, provided that the platform is accessible, for example through a manhole in the top of the tank.

Another problem lies in the construction of the peripheral fastening means for the diaphragm, in view of the requirement that the fastening means should be simple to install by being fully accessible from below the diaphragm, and should be gas-impervious as well as non-interfering and non-harmful with respect to the operation of the diaphragm. Hence, it is another object to provide improved simplified fastening means for the edges of the diaphragm.

According to one feature the platform being embodied in the internal flange appears generally crescent-shaped in plan view with the line of diaphragm fastening following the crescent-shape.

More specifically, the platform presents a relatively gentle or shallow bulge merging with the adjoining circular portions of the flange, and the linear measure of the full circular outline is equal to that of the deviating outline. That is to say, the deviating outline comprises a convex central portion flanked by and merging with a pair of concave portions, the radius of the convexity being larger than the radii of the concavities. The concave portions in turn merge tangentially with the adjoining circular portions of the flange.

According to another feature the vent and sample pipes are disposed within the tank yet outside the edge of the diaphragm by extending through and being sealed in the platform. Also, according to this feature these pipes being rigidly connected with the tank top as well as with the platform provide and constitute supporting members for the platform relative to the tank top.

According to still another feature the internal flange has an inner downward peripheral terminal skirt portion following the deviated outline, and the edge portion of the diaphragm extends ver-

tically downwardly within the skirt portion and is fastened face to face thereto. This permits the diaphragm to be fastened by workmen operating at one side of the diaphragm only, namely underneath where they can support themselves as by ladders or scaffolding from the tank bottom. Also, this eliminates the danger of tools or other items falling onto the diaphragm and damaging the same, and whence they are difficult to retrieve.

In summary, this invention provides an internal marginal platform for the tank, which platform extending from the tank wall in effect merges with a corresponding inwardly bulging edge portion of the diaphragm. This platform serves a three-fold purpose, namely providing straight vertical access for the sampling pipe and for the pressure equalizing pipe into the fluid holding space beneath the diaphragm, whereby the pipes in turn furnish structural support for the platform; providing an observation and maintenance platform; and providing by way of a platform manhole simple and direct passage means between the lower and the upper tank spaces. The edge portion of the diaphragm is fastened to the downward skirt portion of the horizontal flange in such a manner that it can be manipulated or fastened by a crew wholly operating from the bottom of the tank and from underneath the diaphragm.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

In the drawings:

Figure 1 is a perspective view of the tank with a portion of the tank wall broken away to show the platform construction and the diaphragm in an intermediate condition depending from its marginal fastening means.

Figure 2 is a plan view of the tank of Figure 1 with the top partly broken away to show the platform as viewed from above.

Figure 3 is an enlarged side view of the tank of Figures 1 and 2 with a wall portion broken away to show the platform in vertical section indicating the manner of fastening the edge portion of the diaphragm to the platform and to the flange.

Figure 4 is a greatly enlarged detail plan view of the platform showing more clearly the deviating crescent-shaped configuration thereof relative to the circular flange.

Figure 5 is a section of the platform with diaphragm fastening taken on line 5-5 of Figure 4.

Figure 6 is a section of the flange with diaphragm fastening taken on line 6-6 of Figure 4.

Figure 7 is a diagrammatic vertical sectional view of a tank exemplifying a diaphragm with concentric fold contacting the liquid in the tank.

Figure 8 is a diagrammatic vertical sectional view of a tank with dome exemplifying a diaphragm deformable by the pressure of vapor forming above the liquid level.

A closed round metal tank 10 equipped with a diaphragm 11 of flexible material such as rubber sheeting exemplifies the environment of this invention. The tank has a bottom 12, an upright cylindrical wall 13 and a fixed top 14. A horizon-

tal flange 15 having a downward skirt portion 16 is peripherally welded to the inner face of the tank wall 13 at an elevation intermediate the height of the wall, and the edge portion E of the diaphragm is gas-imperviously fastened to the skirt portion 16. The diaphragm 11 may be of bucket shape as indicated in Figure 3, comprising a cylindrical body portion 17 and a substantially flat bottom portion 18, this diaphragm being capable of adjusting itself by deformation to a forming liquid level in the tank, for example by correspondingly varying circumferential fold 19 of correspondingly indicated at D₁ and D₂ in Figure 3.

The edge portion E of the diaphragm as shown in Figure 3 as well as in Figures 5 and 6 has an outwardly and downwardly turned-over cuff-like terminal portion 20 fastened face to face to the downward skirt portion 16 of the horizontal flange 15. The fastening means comprise a flat holding strip 21 of suitable resiliently deflectable material such as a metal strip, bolts 22 with washers 22^a and 22^b, as well as nuts 23, and with a compression coil 23^a interposed between washers 22^a and 22^b. However, the spring washers may be formed as a single piece unitary with a compression coil, or they may constitute a compression coil spring.

The horizontal flange 15 is basically circular and is relatively quite narrow along the major portion of its periphery, namely over a portion or circular length defined by the obtuse angle A₁ in Figure 2, but the flange deviates inwardly from the circular contour by forming what in the plan view of Figure 2 appears as an inward shallow bulge the extent of which peripherally measured may be defined by the acute angle A₂ in Figure 2, which deviation is large enough to provide a platform 24 accommodating a manhole 25 therein provided with and closed by a removable manhole cover 26, adapted to tightly close the manhole 25.

Symmetrically disposed with respect to the manhole 25 are a sampling and gauging pipe 27 and a pressure-equalizing pipe 28. The purpose and function of such pipes per se are well known in the art and need not here be explained except by saying that samples of the tank content can be obtained by reaching through the sampling pipe, and that the pressure-equalizing pipe takes care of varying pressure conditions underneath the diaphragm, which are due to variations in tank contents and variations in pressure. Indeed, the sampling pipe has another important purpose, namely that of gauging the liquid level or height of liquid in the tank to furnish a measure for determining the amount of gasoline or oil added or withdrawn, or bought, sold, or transferred; usually such a level or height determination is made by lowering a tape having attached thereto a plumb bob or a combination sampling bob through the sampling pipe until it reaches the bottom of the tank or a sub platform, and then determining the height of liquid which is indicated on the tape by a mark on a special paste which is rubbed onto the tape. However, in the present instance these two pipes assume additional importance because of the special manner in which they have been embodied in the environmental construction according to this invention, namely their structural relationship to the platform 24. That is to say, these pipes according to this invention must penetrate not only the fixed top of the tank but

also the platform 24 and while doing so they are welded fluid-imperviously into both the top 14 and the platform 24, so that according to this invention they assume the added function of serving as supporting members or stays for the platform 24, so that this platform will safely support the load of an operator or tank inspector or of a working crew. A manhole 29 with tight closing cover is also provided in the top 14 of the tank and disposed directly above the manhole 25 in platform 24.

Referring more particularly to the platform 24 as shown in the detailed Figure 4, it is to be noted that the actual length of the curved outline of the inner edge of that platform, that length being indicated at L₁, is to be equal to the length L₂ of the corresponding circular arch portion P (shown in dot-and-dash), both lengths L₁ and L₂ having as a common basis of comparison the extent of the aforementioned angle A₂. According to this invention the edge portion of the diaphragm is carefully measured and cut to present a full circle equal to the circular diameter of the skirt portion 16 of flange 15. Yet this circular outline will fit and adjust itself to the length L₁ of the deviating outline or bulge presented by the platform 24 defined above, and in a manner that a smooth and foldless fitting of the diaphragm edge portion along its peripheral line of attachment to the tank wall is attainable.

The configuration of the deviating curved outline O of the platform comprises a convex middle portion O₁ and a pair of concave end portions O₂ and O₃, the convex portion merging smoothly with the concave portions, the concave portions in turn merging smoothly with the adjoining circular portions of the flange 15. Moreover, the shape of this configuration of the curved outline of the platform is further qualified by the fact that the radius R of the intermediate convex portion O is appreciably larger than the radii R₁ and R₂ of the adjoining concave portions O₂ and O₃.

The maximum horizontal extent of the platform 24 from the tank wall inwardly is indicated at H, the platform thus to afford sufficient space for an operator or a crew to conveniently stand on. In this way an operator may inspect and survey the condition of the diaphragm from the platform 24, after he has lowered himself on to that platform through the upper manhole 29 in the tank top. By way of this platform, namely through the manhole 25 therein, the operator may descend directly into the space beneath the diaphragm, or a crew below may communicate with a crew above.

The man or crew when engaged in fastening the diaphragm, is thus enabled to work wholly from underneath the diaphragm while deriving safe working support from the tank bottom and without having to step upon the diaphragm or otherwise exposing the same to potential damage. For example, any tools or materials, if they should slip from the workman's grasp, will thus fall upon the tank bottom whence they can be readily retrieved without having done any damage to the diaphragm, rather than falling upon the diaphragm from above in which case the diaphragm may be damaged and retrieving is much more difficult. Furthermore, the tank interior may be scavenged in order to displace gas therefrom, by fresh air being forced sequentially through the lower and the upper tank spaces by way of the platform manhole while the same is open and the spaces communicate.

Since the invention revolves around structural features pertaining to the peripheral portion of the diaphragm and the associated fastening means therefor, including the horizontal flange 15 with skirt portion 16 and the platform 24 with manhole 25 and manhole cover 26, it is immaterial with respect to the scope of the invention what shape the diaphragm assumes as it follows, or adjusts itself to variations in the fluid contents of the tank, nor has the exact manner in which the body portion of the diaphragm is tailored or shaped any direct bearing upon the essence of this invention. Therefore, there are indicated in the diagrammatic Figures 7 and 8 respectively two variant modes of instant diaphragm. That is, Figure 7 illustrates the diaphragm M₁ having direct contacting relationship with the liquid in the tank as the diaphragm forms the depending compensating circular and concentric fold already referred to above in conjunction with the embodiment in Figures 1 and 3, whereas Figure 8 shows an example of a diaphragm M₂ as provided in the dome D of the fixed top of a tank, in which case the diaphragm M₂ is of much smaller diameter than the Figure 7 diaphragm M₁, and its deformation is determined and effected by contact with a vapor body of varying volume forming above the level S of the liquid contents proper in the tank.

What is claimed is:

1. A cylindrical tank having a closed top for storing vaporizable liquids, which comprises a liquid-holding space having inlet means for conducting liquid into the space, discharge means for passing liquid from the space, a gas-impervious diaphragm extending from wall to wall of the tank, an inwardly extending flange member gas-imperviously secured to the tank intermediate the height of the tank and having its free edge portion gas-imperviously fastened to the diaphragm so that as subjected to varying fluid-pressure therebeneath the diaphragm can rise and fall through the opening defined by the flange, the flange including a horizontally inwardly protruding platform presenting a bulge in the circular outline of the flange, the bulge merging with the adjoining portions of the flange, the inner edge portion of the bulge being connected to the diaphragm along the outline thereof, a manhole in the platform, a cover for the manhole, and means for sealingly and detachably fastening the cover with respect to the manhole.

2. A tank according to claim 1, in which the platform presents in plan view a relatively shallow convex central portion having on each side thereof a flanking relatively shallow concave portion merging tangentially with the central portion as well as with the adjoining portions of the flange.

3. The apparatus according to claim 2, wherein the linear measure of the full circular outline is equal to that of the deviating outline.

4. Apparatus according to claim 1, wherein the platform in plan view is generally crescent-shaped by being bounded on one side by an arc of the tank while on the other side by a centrally convexly curved bulge flanked on each side by an inwardly extending concave curved portion.

5. Apparatus according to claim 4, wherein the radius of the curvature of the convex bulge is greater than the radius of each of the flanking concave portions.

6. Apparatus according to claim 1, wherein a pressure-equalizing pipe extends from outside the tank top downwardly through the platform, said

pipe having sealed relationship with said top as well as with said platform.

7. Apparatus according to claim 1, wherein a pressure-equalizing pipe extends from outside the tank top downwardly through the platform, said pipe having sealed relationship with said top as well as with said platform, said pipe being rigidly and sealingly connected with said top as well as with said platform to constitute a supporting member for the platform with respect to said top.

8. Apparatus according to claim 1, wherein a liquid-sampling and gauging pipe extends from outside the tank top downwardly through the platform, said pipe having sealed relationship with said top as well as with said platform.

9. Apparatus according to claim 1, wherein a liquid-sampling and gauging pipe extends from outside the tank top downwardly through the platform, said pipe being rigidly and sealingly connected with said top as well as with said platform to constitute a supporting member for the platform with respect to said top.

10. Apparatus according to claim 1, wherein a pressure-equalizing pipe and a liquid-sampling and gauging pipe extend from outside the tank top downwardly through the platform to a point therebeneath, said pipes being rigidly and sealingly connected with said top as well as with said platform to constitute supporting members for the platform with respect to said top, said pipes being disposed substantially symmetrically with respect to the central portion of the platform.

11. Apparatus according to claim 1, wherein a pressure-equalizing pipe and a liquid-sampling and gauging pipe extend from outside the tank top downwardly through the platform to a point therebeneath, said pipes being rigidly and sealingly connected with said top as well as with said platform for serving as supporting members for the platform with respect to said top and also being disposed substantially symmetrically with respect to the central portion of the platform.

12. A cylindrical tank having a closed top for storing vaporizable liquids comprising a liquid holding space having inlet means for conducting liquid into the space and discharge means for passing liquid from the space, a gas-impervious diaphragm extending from wall to wall of the tank, an inwardly extending flange member gas-imperviously secured to the tank intermediate the height of the tank and having a downwardly extending flange on its inner end, openings in the downwardly extending flange for receiving bolts, the free edge of the diaphragm extending downwardly toward the bottom of the tank and lying adjacent the inner surface of the downwardly extending flange, a flat ring overlying the free edge of the diaphragm, bolts passing through the ring, diaphragm and openings in the downwardly extending flange to thereby gas-imperviously fasten the diaphragm to the inwardly extending flange so that the diaphragm can rise and fall through the opening defined by the flange as it is subjected to varying fluid pressure therebeneath, the flange including a horizontally inwardly protruding platform presenting a bulge in the circular outline of the flange and having a downwardly extending flange integral therewith, the bulge merging with the adjoining portions of the flange with the diaphragm connected to the downwardly extending flange of the bulge along the outline thereof, a pressure-equalizing pipe and a liquid sampling and gauging pipe extending from outside the tank downwardly

75

through the tank and through the platform to a point therebeneath, the pipes being rigidly and sealingly connected with the top and with the platform and serving as supporting members for the platform with respect to the top, the pipes being disposed substantially symmetrically with respect to the bulge in the circular outline of the flange, a manhole provided in the platform and disposed in the space intermediate the pipes, a cover for the manhole, and means for sealingly and detachably fastening the cover to the manhole, whereby repairs to the lower portion of the tank or diaphragm may be accomplished by a repairman passing through the manhole into the lower portion of the tank and underneath 15 the diaphragm.
